Maurice J. Tanner

UNITED STATES PATENT OFFICE

ALBERT W. BAILEY, OF NEW HAVEN, CONNECTICUT

SUPPORT FOR CHAIRS, STANDS, AND THE LIKE

Application filed March 22, 1929. Serial No. 349,247.

The present invention consists of a device for preventing the accidental toppling over of chairs, stands and the like and one of the objects of the invention is to provide a device which will operate automatically and 5 instantaneously when said chair or the like is tilted.

According to this invention, the improved device comprises a prop which is arranged 10 to be easily attached to an ordinary chair, for example, particularly an infant's high chair but the invention may, however, be used with advantage for other articles such as smoking stands. Furthermore, in some 15 instances, it may be desirable to employ several props, one on each side, if desired, so as to support the chair or the like in either a side, back, or front tilted position.

The invention will be hereinafter more 20 fully described with reference to the accompanying drawings, wherein—

Figure 1 is a perspective view showing the improved device as applied to an infant's high chair, and

Figure 2 is a side elevation showing the improved device and a part of the chair.

Referring to said drawings, the article to be supported in this case is an infant's high chair 1 having a back 2, seat 3 and legs 4. 30 The auxilliary support or prop for the chair comprises a pair of parallel bars 5 which are united by tie bars 6 so as to provide a rigid structure. Said prop is hinged at 7 to the plate 8 which, in turn, is preferably secured to the back 2 of the chair. Said hinge 7 has the spring 9 associated therewith so as to form an ordinary spring hinge.

In Figure 1 of the drawings the supporting prop is shown as being in its open position and in Figure 2, in its closed position. 40 In the closed position, the spring 9 is under tension and there is, therefore, a tendency for the spring to throw the prop outwardly. The prop is, however, held in its closed position by means of the pawl 10 which is pivotally mounted, preferably on the underside of a fixed member of the chair, such as the board 11. A spring 12 tends to hold the pawl 10 downwardly so that the notch 50 13 at the end thereof engages the lowermost

tie bar 6. A trip 14 is carried by or connected with said pawl and arranged so that the extended foot 15 thereof will lie in the same plane as the end of the legs 16 of the chair. It is required that the prop, when in 55 its open or operative position, should be braced and for this purpose, the pivoted folding brace member 17 is employed. This member is bent so as to provide an intermediate or straight portion 18 and legs 19 60 lying at right angles to said straight portion. The latter portion passes through elongated slots 20, one in each of said parallel bars 5. With this arrangement, the brace will open to its fullest extent to firmly 65 brace the prop in its operative position and due to the length of the slots 20, the brace will fold up against the back of the chair along with the prop.

In the operation of the improved device, 70 it will be understood that the foot of the trip device 14, being in the same plane as the end of the rear legs of the chair, it is only required that the chair should be tilted slightly in a backward direction when the 75 trip will raise the pawl so as to disengage the same.

The spring hinge or any other spring actuated means employed, as may be desired and required according to the size and 80 weight of the prop, will be arranged to operate to instantaneously throw the prop outwardly when the chair is tilted.

Various modifications may be made in carrying out the details of the invention 85 hereinbefore described but it is to be understood that any modification coming fairly within the terms of the appended claims shall be covered thereby.

I claim—

1. A supporting means for chairs, stands or the like comprising an auxiliary spring operated leg or prop; means comprising a latch for retaining said leg or prop in its closed position; a tripping means for releasing said latch operating automatically and means comprising a spring normally under tension for throwing said leg or prop into its open or supporting position.

2. A supporting means for chairs, stands 100

or the like comprising an auxiliary hinged leg or prop arranged to swing outwardly by action of a spring normally under tension, latching means engaged by a tripping device for holding said leg or prop in a closed position; self-acting means for releasing said tripping device when said chair or stand is tilted and a folding member arranged to brace said leg or prop, when the latter is in its open or supporting position.

10 3. A chair comprising a back, a seat with supporting legs, a prop forming an auxiliary support for said chair, said prop being composed of a pair of parallel side members united by tie bars, said prop in its inoperative position being folded against said chair, a spring retained under tension in the folded position of said prop, means for keeping said prop in its folded position and means comprising a trip for automatically releasing said prop to permit opening thereof under action of said spring when said chair is tilted into an angular position.

15 4. A chair comprising a back, a seat with supporting legs, a folding prop arranged to automatically open to support the chair in a tilted position, said prop being composed of a pair of parallel side members united by tie bars, said prop in its closed position being folded against said chair, a spring retained under tension in the folded position of said prop, means for keeping said prop in its folded position and a pivoted brace for said prop arranged to fold with said prop.

20 Signed at New Haven, county of New Haven, State of Connecticut, this eleventh day of March, 1929.

25 ALBERT W. BAILEY.
